(57) **CLAIM**

The ornamental design for a “beverage bottle,” as shown and described.

DESCRIPTION

FIG. 1 is a top, front, and left side perspective view showing our new design for a beverage bottle;

FIG. 2 is a front view of the beverage bottle shown in FIG. 1, the rear view being a mirror image thereof;

FIG. 3 is a left side view of the beverage bottle shown in FIG. 1, the right side being a mirror image thereof;

FIG. 4 is a top view of the beverage bottle shown in FIG. 1; FIG. 5 is a bottom view of the beverage bottle shown in FIG. 1;

FIG. 6 is a top front left side perspective view of a beverage bottle showing a second embodiment of our new design in a smaller volume; and,

FIG. 7 is a top front left side perspective view of a beverage bottle showing a third embodiment of our new design in a larger volume.

The broken lines in the drawings are included for the purpose of illustration and form no part of the claimed design.
